UNITED STATES PATENT OFFICE.

JOHN BERGER AND JOHN C. LUCE, OF TOLEDO, OHIO.

PASTING MACHINE.

Application filed July 23, 1924. Serial No. 727,621.

This invention relates to coating applying apparatus.

This invention has utility when incorporated in a machine for applying coating, 5 as of adhesive or paste, to strips of material, as wallpaper.

Referring to the drawings:—

Fig. 1 is a side elevation of an embodiment of the invention as a wallpaper pasting machine;

Fig. 2 is a perspective view of the reservoir, well, or fountain for the paste supply;

Fig. 3 is a vertical section longitudinally through the fountain or well with the strip 15 material and paste handling elements therein;

Fig. 4 is a perspective view of the cutter or knife;

Fig. 5 is a plan view of the apparatus of 20 Fig. 1, parts being broken away; and

Fig. 6 is an elevation of the opposite end of the device to the showing in Fig. 1, with the apparatus control open, parts being broken away.

Legs 1 may support housing 2 having therein receptacle 3 as a well or reservoir for adhesive or paste 4 normally maintained at a level considerably below dip portions 5 in the sides of the housing 2. This well or 25 reservoir 3 is a unit from which the rest of the apparatus is readily removed so that this well may be conveniently cleansed, as well as for supply of material thereto. Furthermore, in the removal condition, the other elements of the machine are more readily accessible for cleaning up after use so that adhesive may not dry therewith to detract from the proper operation of the machine.

Side plates 6, 7, are connected by four bars 40 8 to maintain this structure as a rigid rectangular frame. Centrally of this frame and in its lower portion, is shaft 9 carrying roll 10. As the side plates 6, 7, are placed in the open top of the reservoir 3, these 45 plates contact the upper curved portions of this reservoir above the level of the liquid 4 with the roll 10 extending downward therefrom not fully to the bottom of the reservoir 3, but for partial submergence in this 50 paste 4 in the reservoir 3.

Plate 6 has fixed therein trunnion seat 11 in the inner end of trunnion 12 adjustable as to its inward distance by set screw 13 in collar 14 fixed with the plate 6. This adjustment of the trunnion 12 axially permits

placing of the seat 11 at a desired distance inward from the end of the paste applying roll 10 with which this trunnion 12 is axially parallel.

The plate 7, opposing the plate 6, has slot 60 15 therein so that strip material supporting shaft 16 may have end 17 thereof adjacent flange 18 inserted in the seat 11, while opposing flange 19 is yieldably thrown by spring 20 against roll of strip material 21 65 and thus may yieldably adjust such roll of strip material axially as the spring 20 contacts with washer 22 in the shifting of the shaft 16 downward for aligning with the trunnion 12.

This strip material, as wallpaper 21, on the supporting means supply roll or shaft 16, when wrapped thereon with its back or paste receiving side outward, has such paste receiving side directed upward for arc contact with the paste receiving or first roll 10 as protruding beyond the width of this strip material not only toward the plate 6, but also toward the plate 7. In passing over this arc contact portion, this strip material 80 21 may travel downward to have the paste coated portion away from rotary guide element or second roll 23 on shaft 24 as mounted for rotation between the plates 6, 7.

This shaft 24 extends to ride free of slots 85 25 in the plates 6, 7, but for bearing is directly supported in auxiliary plate sections 26 having hooks 27. These plate sections 26 are mounted on aligned hinge pins 28 for swinging as to the frame 6, 7, 8.

The element 23 as fixedly mounted on the shaft 24 carries outside the plate 7 gear wheel 29 in mesh with gear 30 fast on the shaft 9. The ratio between these gears 29, 30, is such that, in the lineal travel of the strip material 21 from the supporting means 19 as one guide about the element 23 as companion parallel guide for effecting arc contact for the material 21 upon the roll 10, this travel of the strip material as to the 100 roll 10 is at a slightly different rate than the lineal speed of the periphery of the roll 10. This driving of the roll 10 is directly effected by the pulling of the strip of material 21 about the guide element 23 for thereby causing the element 23 to act as a driver. This difference in travel rate between the paste applying roll 10 and the strip material 21 assists in the uniform spreading of the 105 paste on the under side of paste receiving

side of the strip material. The hook mounting 27 for the shaft 24 in the frame plates 26 is such that when such frame plates 26 are swung upward from the frame 6, 7, 8, on 5 the pivots or hinges 28, the roller element 23 may be readily removed for cleansing.

Mounted on the hinge pins 28 by arms 31 is bar 32 parallel with the shaft 24 and carrying wiper of fiber or woolen 33 of an extent greater than the width of the strip material 21. This wiper 33 by its gravity fall upon the paste coated side of the material tends to spread out such material into a thin, smooth coat. The thickness of this coat is 15 conveniently and readily adjusted by the speed or draw of the free end of the strip material as drawn from the element 23. A rapid rate of drawing means that the coating of paste will be thicker than with a 20 slower rate of drawing.

The paste applying roll 10 as wider than the strip material 21 insures the applying of the paste fully to the edges of the strip material 21. The fact that the rotary guide element 23 is narrower than the strip material precludes any end slopping of paste upon such roller 23 and thereby keeps such paste from the front side of the paper or strip. The wiper 33 accumulates the surplus paste and as this wiper is not only longer than the element 23 but of an extent greater than the length of the strip material, this paste accumulation extends to the portion of the wiper 33 beyond the width 35 of the strip material.

Ends 34 of the guide element 23 are countersunk thereby giving overhang provision for the rotary element 23. Extending from this overhang region and below the ends of 40 the wiper 33 is bulge 35 for receiving any dripping of paste from the wiper 33 and directing such dripping back into the reservoir 3 as clear of the strip material. This conical bulge 35 is mounted in fixed position 45 with the roll 23 on the shaft 24.

This strip material 21 as drawn from the rotary guide element 23, passes over bars 36, 37, as providing a slot or seat 38 therebetween to way 39 as a shield over the roll 50 10 and the support 16. This shield 39 is, as well as the bars 36, 37, fixed with the plates 26. This shield 39 forms an initial way or table. The housing 2 carries flange 40 which may be connected to sectional extension 41, 42, as a further continuation of 55 the way 39 upon which the unpasted side of the strip material may rest as drawn through the pasting machine. The extent of this drawing of the strip material for 60 matching design at desired strip lengths may be checked by gage 42 as carried by the way sections 41, 42. These sections 41, 42, may be mounted upon a paper hanger's table 43 or be otherwise supported as may 65 be found desirable in practice.

When the desired length of material as to the drawn out position on the gage with the matching factor has been taken into account, such withdrawal may be stopped. The pasted portions of the paper may be 70 folded against each other. On the hinge pins 28 adjacent the arms 31 is a pair of arms 44 carrying therebetween knife 45 having centering portion 46 herein shown as protruding symmetrically of the way for 75 the strip material 21. The strip length as determined is severed by a swing of the arms 44 so that the knife 45 enters the slot or seat 38 in effecting a quick severing of the pasted length. The knife may be quickly drawn 80 back and further strips drawn for cutting as the pasted material is allowed to soak up before being applied to the wall. The point 46 of the knife 45 being mid-way of the width of the strip material, there is no tendency in the cutting of the material to shift it from one side toward the other of the machine. Accordingly, the central position as 85 adjusted by the trunnion 12 for the strip material is a position maintained in the travel 90 of the material from the machine.

The device is one of simple construction capable of a speed of operation such that over hand pasting the capacity of work for the hanger may be increased fifty percent. Furthermore, the pasting is of a smoothness and uniformity to the paper edge not attainable in hand pasting, and there is, accordingly, utility in the superior character 95 of the pasting as well as the speed of performing such herein.

From the foregoing it will be seen that in the operation of this machine for applying a coating of paste to wallpaper, it is not material whether or not the paper is untrimmed 105 as to both sides, trimmed as to one side, or trimmed as to both sides, for the machine as operating hereunder is effective for applying over the entire surface and up to the edge whether trimmed or not, a uniform 110 coating of the adhesive. This means that whether or not the paper to be applied be lapped or abut, there is paste over the entire surface as applied to the wall clear up to the edge. However, there is no slopping of 115 the paste beyond the edge, under any circumstances, in the operation of the machine as disclosed.

What is claimed and it is desired to secure by Letters Patent is:—

1. A paste reservoir, a frame comprising a pair of parallel plates disposed in and supported by said reservoir, said plates providing bearings, and strip material directing and paste delivering means removably mounted in said frame bearings, bolts assembling said plates to maintain the bearings in aligned pairs.

2. A paste reservoir having walls upwardly extending from a pool region therein, a

- frame extending into said reservoir and removably mounted on said upwardly extending walls above said pool, and strip material directing and paste delivering means carried by said frame as a unit independently removable against clogging in disuse and to leave clear access to the pool.
3. A paste reservoir having walls upwardly extending from a pool region therein, a frame extending into said reservoir and removably mounted on said upwardly extending walls above said pool, a paste delivery roll rotatably mounted in the frame for partial submergence in paste in said reservoir, a strip material support on one side of the roll, and a strip material guide on the opposite side of said roll disposed for directing strip material from the support to the guide for arc contact with the portion of the roll which may be out of submergence in the paste, said roll and guide being assembled by said frame as a unit independently removable against clogging in disuse to leave clear access to the pool.
4. A paste reservoir having walls upwardly extending from a pool region therein, a frame extending into said reservoir and removably mounted on said upwardly extending walls above said pool, a paste delivery roll rotatably mounted in the frame for partial submergence in paste in said reservoir, a strip material support on one side of the roll, a strip material rotatable guide on the opposite side of said roll disposed for directing strip material from the support to the guide for arc contact with the portion of the roll which may be out of submergence in the paste, and a drive from the guide for the roll, said roll and drive being assembled by said frame as a unit independently removable against clogging in disuse to leave clear access to the pool.
5. A paste reservoir having walls upwardly extending from a pool region therein, a frame extending into said reservoir and removably mounted on said upwardly extending walls above said pool, a paste delivery roll rotatably mounted in the frame for partial submergence in paste in said reservoir, a strip material support on one side of the roll, a strip material rotatable guide on the opposite side of said roll disposed for directing strip material from the support to the guide for arc contact with the portion of the roll which may be out of submergence in the paste, a drive from the guide for the roll, and a slippage effecting drive from the guide for rotating the roll in the direction of strip material travel thereover and at a different linear speed than said strip material, said roll and drives being assembled by said frame as a unit independently removable against clogging in disuse to leave clear access to the pool.
6. A pasting machine embodying a paste applying roll, a strip material support adjacent said roll, a strip material rotated guide oppositely disposed as to the roll from said support for providing arc contact of the strip material on said roll, and connections from the guide for rotating the roll at a slippage effecting rate as to the strip material passing thereover.
7. A pasting machine for strip material comprising a paste applying roll, and strip directing means comprising a rotary element for engaging the opposite side of the strip material from that engaging the roll, said rotary element being narrower than said paste applying roll and the strip material being of an intermediate width.
8. A pasting machine for strip material comprising a paste applying roll, strip directing means comprising a rotary element for engaging the opposite side of the strip material from that engaging the roll, said rotary element being narrower than said paste applying roll and the strip material being of an intermediate width, a wiper of greater extent than the material width coacting with the material on said rotary element for spreading and removing excess paste, said rotary element being terminally overhung, and a deflector in said overhang region for directing paste accumulation from the wiper beyond the strip material width against falling on said strip material.
9. A paste fountain, a first roll movable out of said fountain, additional rolls for directing a strip of material for arc contact outside said fountain with said first roll, and gearing actuatable from one of said additional rolls as an actuating roll peripherally operating at the lineal travel rate of said strip material for actuating said first roll at a different peripheral speed from the peripheral speed of said actuating roll, whereby the pasting roll may have a wiping action as to the strip of material.
10. A paste reservoir, a paste delivering first roll extending therefrom, supply and second rolls parallel to said first roll providing a way for a traveling strip of material from the supply roll for arc contact with said first roll thence about said second roll peripherally operating at the lineal travel rate of said strip material, and toothed gearing from the second roll to the first roll controlling the peripheral speed of the first roll as different from the peripheral speed of the second roll, whereby the pasting roll may have a wiping action as to the strip of material.
11. A machine comprising axially parallel strip material rotatable supporting means, a strip material coating roll, and a rotary guide, a gage disclosing way from said guide, a swingable cutter, and means mounting the cutter on the machine axially parallel to said rolls, normally clear of the

strip material, and movable toward, said guide to sever a way supported portion of the strip material as passing from said guide and overlapping said gage disclosing portion of said way.

12. A machine comprising axially parallel strip material rotatable supporting means, a strip material coacting roll, and a rotary guide; a gage disclosing way from said guide having a transverse fixed seat providing portion adjacent the guide, a bearing

fixed with the machine parallel to said rotary guide, a knife and arms mounted in said bearing and extending to carry the knife to be thus centered transversely normally clear of a strip of material and swingable for co-acting with said seat in severing the strip of material. 15

In witness whereof we affix our signatures.

JOHN BERGER.
